UNITED STATES PATENT OFFICE.

WILLIAM H. PEARCE, OF CHICAGO, ILLINOIS.

HEAT-DISTRIBUTING SYSTEM.

No. 891,855.

Specification of Letters Patent. Patented June 30, 1908.

Application filed September 19, 1906. Serial No. 335,220.

To all whom it may concern:

Be it known that I, WILLIAM H. PEARCE, a citizen of the United States, residing at Chicago, in the county of Cook and State of Illinois, have invented certain new and useful Improvements in Heat-Distributing Systems, of which the following is a full, clear, and exact specification.

This invention relates to improvements in heat distributing systems, and more particularly to that class of systems in which the heating medium is delivered to the different points of use from a central generating plant or station through pipes or conduits located beneath the surface of the ground.

The object of the same is to provide an improved arrangement of the pipes or conduits which will be compact, thereby necessitating a minimum amount of space, and at the same time to provide an improved means for protecting the pipes.

A further object is to provide an improved protecting covering spaced from the pipe or conduit which conveys the heating medium, and which will be so arranged as to completely surround the pipe.

A further object is to provide improved means for anchoring the pipe or conduit, and at the same time allow the pipe or conduit, together with its covering or casing, to expand and contract.

A further object is to provide an improved system which will be simple and cheap to construct or install, and efficient in operation.

To the attainment of these ends, and the accomplishment of other new and useful objects, as will appear, the invention consists in the features of novelty in the construction, combination and arrangement of the several features hereinafter more fully described and claimed and shown in the accompanying drawings illustrating the embodiment of this invention, and in which,

Figure 1 is a transverse sectional view of a system constructed in accordance with the principles of this invention; Fig. 2 is an elevation of a portion of a system similar to that shown in Fig. 1, and illustrating the manner of anchoring the pipe or conduit; Fig. 3 is a detail sectional view of the casing for the return pipe showing the means for supporting the pipe intermediate its couplings, and with the pipe and coupling in elevation; Fig. 4 is a top plan view of a section of a system showing a slightly different arrangement;

Fig. 5 is a detail sectional view of a portion of a ventilated covering or casing; Fig. 6 is a sectional view on line 6—6 of Fig. 1; Fig. 7 is a sectional view on line 7—7 of Fig. 1; Fig. 8 is a transverse sectional view through the 60 couplings; Fig. 9 is a bottom plan view of the supplemental pipes and couplings; Fig. 10 is a detail sectional view of the manner of connecting the sections of the casing.

Referring to the drawings, the same reference characters designate similar parts throughout the several views.

In installing an improved system of this character, as exemplified by Fig. 1 of the drawings, a suitable drain tile 10 is placed in 70 the bottom of an ordinary trench or ditch, and covered in the usual manner. A casing 11 is then provided above the drain tile which is adapted to receive the system return pipe 12. This casing is preferably open 75 at the top, and may be constructed of any suitable material, and in any desired manner, either by molding the same directly within the ditch in the wellknown manner, or by constructing the same of sections formed in 80 the shape of tiles, and assembled.

Suitable ribs or projections 13 may be provided at intervals intermediate its length, of a sufficient height to form a support for the pipe 12, intermediate its couplings 14, as 85 more clearly shown in Fig. 3 of the drawing. The internal diameter of this casing 11 is of such a size as to receive and completely house the pipe 12.

Suitable tiles 15 adapted to receive conductor or other wires are arranged on each side of the casing 11, and the tops of these tiles 15 are preferably arranged so as to be flush with the top of the sides of the casing or housing 11, to form an even surface upon 95 which a base or support 16 rests. This base or support may be formed in any desired manner and of any thickness, either by constructing the same of plastic material within the trench, or in the form of tiles suitably 100 assembled, and is preferably of a width to project beyond the sides of the conductor-wire tiles 15. A suitable depressed or caved portion 17 is provided in the upper face of the base or support 16 and shoulders 105 18 are provided adjacent the sides of said depressed portion, which latter project slightly above the upper face 19 thereof. A plate 20 of any suitable material, such as metal or the like, is placed upon the base or 110

support 16, within the concaved or depressed portion 17, and is of a width less than the width of the said portion 17.

A cover is provided for the plate 20, which 5 is composed of any suitable fibrous material 21, such as wool, felt, or the like, and secured to one face thereof is a strip of metal 22, such as tin or the like. If desired, a suitable fireproof material 23, such as asbestos or the like, may be interposed between the material 21 and the metal 22. The fibrous covering 21 is of a width greater than the width of the plate 20 and less than the width of the concaved or depressed portion 17, and is 10 placed over the plate 20 with the fibrous material adjacent the plate, and is compressed so that the portion of the material beyond the sides of the plate will contact with and rest upon the bottom of the concaved or depressed portion 17 of the base or support 16, as will be understood.

The material 21 and the metal 22 are provided with a plurality of registering apertures 24, suitably spaced from each other 25 and are of a length less than the width of the plate 20.

Suitable rollers 25 may be placed within the apertures 24, so as to rest upon the plate 24, of a size to move freely in the apertures 30 and project above the top of the plate or cover 22. A pipe or main 26 of any desired size, and preferably covered with a suitable fireproof material 27, such as asbestos or the like, is placed upon and supported by the 35 rollers 25, which latter form bearings for the pipe or main when moving during contraction and expansion.

A suitable casing is provided for the pipe or main 26, which is constructed of a suitable fibrous material 28, and preferably provided with a water proof outer face 29, of any suitable material, such as tar paper or the like, and secured to the other face is a metal plate 30, such as tin or the like. If 40 desired, a suitable fireproof material 31, such as asbestos or the like, may be interposed between the adjacent faces of the fibrous material 28, and the metal 30, in order to protect the fibrous material from 45 the heat of the metal. This casing may be constructed in flat form, and, when desired for use, bent or bowed into arch-shape, as shown, and placed over the pipe in such a position that its extremities will rest within 50 the concaved or depressed portion 17 of the base or support, and between the edges of the material 21, and the edges of the portion 17 and shoulders 18, in such a manner that the casing formed thereby will be spaced 55 from the main or pipe 26.

A suitable wall 32 may be provided for covering or inclosing the casing, and said wall is supported by the face 19 of the base or support 16, and is arched over the outer 60 face of the casing, and in contact therewith.

This wall or arch may be constructed by forming the same of plastic material within the trench, in any wellknown manner, or may be formed into blocks or tiles and assembled.

If constructed of tiles, the tiles are preferably formed with shouldered portions 33 adapted to receive or accommodate the shoulders or projections 18, as will be understood.

The wall or arch 32 is so constructed and arranged that its outer face substantially forms a continuation of or is flush with the outer edges of the base or support 16, and a suitable waterproof covering 34, such as asphaltum, or the like, is placed over the outer edges thereof, to prevent water or moisture percolating therethrough and contacting with the casing around the pipe or main 26.

Obviously, the arch 32 may be constructed in sections, and if so constructed the sections may be provided with overlapping portions 35-36 to form a joint, as shown in Fig. 7.

The casing which covers the pipe 26 may also be of sectional construction, and if so the ends thereof may be placed together, as shown in Fig. 7, and the tar paper or covering 29 of one section may overlap the adjacent end of the next section, from which the paper or covering has been omitted, and thus suitably secured, as will be understood.

If desired, the fibrous material 28 forming the pipe casing may be constructed in the form of a ventilated casing, a section of 100 which is shown in Fig. 5.

Suitable couplings 37 may be provided throughout the length of the system, which rest upon a suitable support 38, which latter is secured to a base 39 by any suitable means, such as bolts 40, or the like, passing through the support 38 and engaging anchor plates or bars 41 embedded in the base 39.

The couplings 37 are secured to the supports 38 in any suitable manner, such as by means of bands or ears 42 on the coupling, and tie bolts or rods 43 engaging the same, and the support 38. The supports are preferably of such a height as to permit the return pipe 12 to pass through the support 115 between the base 39 and the coupling 37. The support is provided with an aperture or cutout portion 44 to permit a branch pipe 44^a to be secured to the opening 45 of the return pipe, and the coupling 37 may also 120 be provided with a top opening 46 to accommodate a branch pipe 46^a, more clearly shown in Fig. 8. A suitable manhole or housing, designated generally by the numeral 47, is supported by the base 39, within 125 which housing the couplings 37 stand.

The fibrous casing, and the wall 32 which surround the pipe 26, and the casing or housing 11 of the pipe 12, terminate short of the couplings 37, and project through the 130

side walls of the manhole 47, as shown in Fig. 2, and interposed between the edge of the opening through which they pass and the wall or arch 32 is a suitable waterproof 5 protector 48 of any suitable material, such as paper or the like. This protector prevents the end of the casing and the wall of the aperture in the manhole from sticking together and permits the movement of the 10 parts with relation to the wall of the manhole, which movement is due to contraction and expansion, and at the same time prevents water or moisture from passing through the opening, around the wall or 15 arch 32, and contacting with the pipe 26, which would tend to chill the latter. If desired, and as will be understood, a suitable valve 49 may be provided in the coupling.

In the arrangement shown in Fig. 4, the 20 sections 26 constituting the supply pipe or conduit, are arranged out of alignment and are connected by the ordinary elbow joint 50 which latter may, if desired, be provided with a covering 51 of asbestos or any other suitable 25 material applied in a plastic form. These joints or couplings are incased in a suitable housing designated generally by the numeral 32, into which the ends of the covering 28 extend, in a manner similar to that shown by 30 the arrangement in Fig. 2, and any suitable anchors may also be provided for anchoring the sections of the pipe or main 26, intermediate their length.

When it is desired, suitable air pipes 53 35 may be placed within the casing which surrounds the pipe or main 26, and may be used for drawing the air from the system, bent as shown in Fig. 8, so as to pass around the coupling-member 37. With such an arrangement, the heat which is radiated from the 40 pipe or main 26 will be confined within the space between the pipe and the metal facing of the fibrous casing, which facing will direct the heat back against the pipe, thereby tending 45 to maintain the heating medium at a high temperature; the fireproof material or asbestos 31 being provided between the metal facing 30 and the fibrous material 28, in order to prevent the heat of the metal from setting 50 fire to the fibrous material. It will thus be seen that the pipes are not only securely anchored, which does not interfere with their contraction and expansion, but that they are so arranged as to produce such a compact 55 system that the cost of installation is greatly reduced. The casing being so constructed and provided with a flat or straight side, a pipe or main of considerable size may be employed without loss of space. Furthermore, 60 the supply and return pipes are so protected that moisture cannot come in contact therewith from the outside, but the moisture entering the ground will pass around the pipes and find its way to the drain tile.

65 In the exemplification of the invention

shown in Fig. 8, the tiles 15 are dispensed with and suitable water pipes 52—52^a may be employed. These pipes are arranged close to the return pipe 12 and are provided with couplings 54—55, arranged adjacent the 70 couplings 37—45, and within the manhole 47. These couplings rest upon suitable supports 56, and are preferably anchored to the walls of the manhole 47, or any other support, by means of bolts 57. These couplings are provided with a depending portion or chamber 58, one on each, and located adjacent the opposite ends of the respective couplings. Pipes 59 are connected to and communicate with the portion 58 of the coupling 54, and 80 extending beyond both sides of the pipe 52, one of said pipes 59 crossing beneath the coupling 55. Similar pipes 60 connect with the portion 58 of the coupling 55, and extend 85 in a parallel direction with the pipes 59, one of which crosses beneath the coupling 54. Thus it will be seen that either one of these pipes 52—52^a, together with its respective branch pipe, may be used as a supply or return pipe, as desired.

90 Water of condensation from the service pipes 26—46^a will accumulate in the bottom 61 of the coupling members 37, and leading from this portion 61 is a suitable pipe 62, which communicates with a chamber or receptacle 63, which in turn communicates with the return pipe 44^a by means of the connecting pipe 64 and the coupling 65. A suitable sight glass 66 may be provided for the chamber or receptacle 63, and if desired a 100 valve 67 may be provided in the pipe 62. Thus it will be seen that when the valve 67 is opened the water of condensation accumulated in the portion 61 of the coupling member 37 will pass out through the pipe 62, and 105 chamber 63, and into the pipe 44^a. This portion 61 of the coupling member 37 may be tapped on each side to permit the chamber 63 to be connected on either side, or an additional chamber to be used, and when only 110 one chamber is used the unused opening may be closed with an ordinary plug 68, as will be understood.

In order that the invention might be fully 115 understood, the details of an embodiment thereof have been thus specifically described, but

What I claim is:—

1. In a heat distributing system, the combination of a base, a supply pipe supported thereby, a return pipe disposed beneath the base and in proximity to the supply pipe, and a casing for each of the pipes, each of said casings being provided with an open side disposed adjacent each other and said pipes 120 being disposed between and serving to close both of the casings.

2. In a heat distributing system, the combination of a base, rollers mounted upon the base, means for preventing displacement of 130

- the rollers, a supply pipe supported by the rollers, a return pipe disposed beneath the base and in proximity to the supply pipe, and a casing for each of the pipes, each of said casings being provided with an open side and said open sides being disposed adjacent each other, said base being disposed between and serving to close both of the casings.
3. In a heat distributing system, the combination of a base, a supply pipe supported by the base, a return pipe disposed on the opposite side of the base and in proximity to the supply pipe, and a casing for each of the pipes, each of said casings being provided with an open side, said open sides being disposed adjacent each other, said base being disposed between and adapted to close the casings, the casing surrounding the return pipe being provided with spaced ribs or projections throughout its length and upon which said pipe rests.
4. In a heat distributing system, the combination of a supply pipe, anchors for said pipe, housings for the anchors, a casing for the pipe comprising a body portion of fibrous material, a metallic heat deflecting surface and a fireproof material interposed between the body portion and the metallic surface, the extremities of said casing projecting loosely through the wall of the housing and terminating short of the anchors to permit expansion and contraction thereof, and a return pipe for the system.
5. In a heat distributing system, the combination of a supply pipe, anchors for said pipe, housings for the anchors, a casing for the pipe comprising a body portion of fibrous material, a metallic heat deflecting surface and a fireproof material interposed between the body portion and the metallic surface, the extremities of said casing projecting loosely through the wall of the housing and terminating short of the anchors to permit expansion and contraction thereof, a packing interposed between the casing and the edge of the opening in the wall through which the casing passes, and a return pipe for the system.
6. In a heat distributing system, the combination of a supply pipe, a casing for said pipe comprising a body portion of fibrous material, a metallic heat deflecting surface and a fireproof material interposed between the body portion and the metallic surface, an independent protecting covering for the casing, an anchor for the pipe, a housing for the anchor, the extremities of said casing and protecting cover extending into the housing through the walls thereof, and terminating short of the anchor to permit contraction and expansion of the casing, and a return pipe for the system.
7. In a heat distributing system, the combination of a supply pipe, a casing for said pipe comprising a body portion of fibrous

material, a metallic heat deflecting surface and a fireproof material interposed between the body portion and the metallic surface, an independent protecting covering for the casing, an anchor for the pipe, a housing for the anchor, the extremities of said casing and protecting cover extending into the housing through the walls thereof and terminating short of the anchor to permit contraction and expansion of the casing, a packing disposed between the periphery of said cover and the edge of the opening in the wall through which the cover passes, and a return pipe for the system.

8. In a heat distributing system, the combination of a base provided with a depressed portion in its upper face, a heat deflector disposed in the depressed portion, a supply pipe supported above the deflector, a casing for the pipe comprising a flexible member arched over the pipe with its extremities resting in the depressed portion of the base, a heat deflector secured to the face of the casing adjacent the pipe, a return pipe disposed beneath the base, and means for protecting said return pipe and casing from external moisture.

9. In a heat distributing system, the combination of a base provided with a depressed portion in its upper face, rollers in said depressed portion, a heat deflector also within the depressed portion surrounding the rollers and terminating short of the walls of the depression, a supply pipe supported by the rollers, a casing for the supply pipe comprising a flexible material having a heat deflecting surface and arched over the pipe with its extremities standing within the depressed portion between the walls thereof and the edges of the heat deflector therein, a return pipe disposed below the base, and means for protecting said pipe and casing from external moisture.

10. In a heat distributing system, the combination of a base provided with a depressed portion in its upper face, rollers in said depressed portion, a heat deflector also within the depressed portion surrounding the rollers and terminating short of the walls of the depression, a supply pipe supported by the rollers, a casing for the supply pipe comprising a flexible material having a heat deflecting surface and arched over the pipe with its extremities standing within the depressed portion between the walls thereof and the edges of the heat deflector therein, whereby said casing will be closed by the base, a return pipe disposed below the base, a casing for the return pipe also closed by the base, and a protecting cover for the casing of the supply also supported by the base and closed thereby.

11. In a heat distributing system, the combination of a base provided with a depressed portion in its upper face, a casing

supported by the base comprising two sections each of which comprises a body portion of fibrous material and a metallic heat deflecting surface, the bottom section of the 5 casing being disposed within the depressed portion of the base with the deflecting surface uppermost, said section being provided with apertures, rollers in the apertures, a supply pipe supported by the rollers, the top 10 portion of the casing comprising a flexible body portion composed of fibrous material and a heat deflecting surface, said upper portion being bowed over the pipe with its extremities standing between the edges of the 15 bottom portion and the sides of the depressed portion, and a return pipe for the system.

12. In a heat distributing system, the combination of a supply pipe, an anchor for the pipe, a housing for the anchor, a casing for 20 the pipe comprising a body portion of fibrous material, a metallic heat deflecting surface, and a fireproof material interposed between the body portion and the metallic surface, the extremities of said casing projecting 25 loosely through the wall of the housing and terminating short of the anchor.

13. In a heat distributing system, the combination of a supply pipe, a casing for said pipe comprising a body portion of fibrous 30 material, a heat deflecting surface and a fireproof material disposed between the body and the said surface, an independent protecting covering for the casing, an anchor for the pipe, and a housing for the anchor, the 35 extremities of said casing and protecting cover extending into the housing through the wall thereof and terminating short of the anchor.

14. In a heat distributing system, the combination of a base provided with a depressed portion in its upper face, a member disposed in the depressed portion and having a heat deflecting surface, a pipe supported adjacent to said surface, a casing for the pipe comprising a flexible member arched over the pipe 45 with its extremities resting in the depressed portion of the base, and a heat deflector secured to the face of the casing adjacent the pipe.

50 15. In a heat distributing system, the combination of a base provided with a depressed portion in its upper face, a member disposed in the depressed portion and provided with a heat deflecting surface, supports resting upon the base and projecting through the said member, a pipe resting upon the supports adjacent the deflector, a casing for the pipe comprising a flexible member arched over the pipe with its extremities resting in the depressed portion above the base, and a heat deflector secured to the face of the casing adjacent the pipe.

16. In a heat distributing system, the combination of a base provided with a depressed 65 portion in its upper face, a member disposed

in the depressed portion and provided with a heat deflecting surface, a pipe supported adjacent the member, a casing for the pipe comprising a flexible member arched over the pipe with its extremities resting in the depressed portion of the base, a heat deflector secured to the face of the casing adjacent the pipe, and a covering for the casing. 70

17. In a heat distributing system, the combination of a base provided with a depressed portion in its upper face, a member disposed in the depressed portion and provided with a heat deflecting surface, supports resting upon the base and projecting through the said member, a pipe resting upon the supports adjacent the deflector surface, a casing for the pipe comprising a flexible member arched over the pipe with its extremities resting in the depressed portion above the base, a heat deflector secured to the face of the casing adjacent the pipe, and a separate covering for 80 the casing. 85

18. In a heat distributing system, the combination of a supply pipe, a casing for the pipe comprising a body portion of fibrous material surrounding the pipe, means for supporting the pipe out of contact with the casing, the outer face of the casing being water-proofed, and a reinforced plastic covering engaging and surrounding the said casing. 90 95

19. In a heat distributing system, the combination of a supply pipe, a casing for the pipe comprising a body portion of fibrous material having a heat deflecting surface, 100 said casing surrounding the pipe with the heat deflecting surface adjacent the pipe, means for supporting the pipe out of contact with the casing, the outer face of the casing being water-proofed and a reinforced plastic covering engaging and surrounding the said casing. 105

20. In a heat distributing system, the combination of a supply pipe, a casing for the pipe comprising a body portion of fibrous material having a heat deflecting surface, 110 said casing surrounding the pipe with the heat deflecting surface adjacent the pipe, means for supporting the pipe out of contact with the casing, the outer face of the casing being water-proofed, and a re-inforced plastic covering engaging and surrounding the said casing, said covering being also provided with a water-proofed outer surface. 115

21. In a heat distributing system, the combination of a supply pipe, a sectional casing for the pipe, each section comprising a body portion of fibrous material, said casing surrounding the pipe, means for supporting the pipe out of contact with the casing, the outer surface of each section being water-proofed, 120 and a plastic covering engaging and surrounding the said casing. 125

22. In a heat distributing system, the combination of a supply pipe, a sectional casing 130

for the pipe, each section comprising a body portion of fibrous material, the inner face of each section being provided with a heat deflecting surface, said casing surrounding the pipe with the heat deflecting surface adjacent to the pipe, means for supporting the pipe out of contact with the casing, the outer face of each section being water-proofed, and a plastic covering engaging and surrounding the said casing.

23. In a heat distributing system, the combination of a supply pipe, a sectional casing for the pipe, each section comprising a body portion of fibrous material, the inner face of each section being provided with a heat de-

flecting surface, said casing surrounding the pipe with the heat deflecting surface adjacent to the pipe, means for supporting the pipe out of contact with the casing, the outer face of each section being water-proofed, and a sectional reinforced plastic covering engaging and surrounding the said casing.

In testimony whereof I have signed my name to this specification, in the presence of two subscribing witnesses, on this 17th day of September A. D. 1906.

WILLIAM H. PEARCE.
